UNITED STATES PATENT OFFICE.

OTTO E. ROSS, OF SALT LAKE CITY, UTAH.

LAUNDRY TRAY OR TUB.

1,124,812.

Specification of Letters Patent.

Patented Jan. 12, 1915.

Application filed August 11, 1914. Serial No. 856,213.

To all whom it may concern:

Be it known that I, OTTO E. ROSS, a citizen of the United States, residing at Salt Lake City, in the county of Salt Lake and State of Utah, have invented new and useful Improvements in Laundry Trays or Tubs, of which the following is a specification.

This invention relates to a laundry tray or tub, the primary object of the invention being to provide a tray or tub which may be easily and economically constructed of sheet metal, preferably in a single piece, so that it may be sold at a low cost.

A further object of the invention is to provide a tray or tub of the portable variety which may be easily and conveniently handled, which is strong and durable in construction, which is provided with an extended back to prevent the water from splashing out at the rear, and which, in the portable style, may be lifted and transported with greater facility than the old style tubs.

A still further object of the invention is to provide a laundry tray or tub of such construction that any number of tub sections may be joined together to form a divisional stationary tub which may be assembled at the point of use and firmly and securely fixed in the desired position.

The invention consists of the features of construction, combination and arrangement of parts herein fully described and claimed, reference being had to the accompanying drawings in which:—

Figure 1 is a perspective view of a stationary tub embodying my invention, as made up of two tub sections. Fig. 2 is a vertical longitudinal section of the same. Fig. 3 is a horizontal transverse section on the line 3—3 of Fig. 2. Fig. 4 is a perspective view of one of the portable tubs or trays. Fig. 5 is a vertical longitudinal section thereof. Fig. 6 is a vertical front to rear section. Fig. 7 is a plan view of the blank from which the tub is made.

In carrying my invention into practice, I provide a tub or tray comprising a body 1, preferably of general oblong rectangular form, and comprising a bottom 2, inclined or sloping front wall 3, a vertical rear wall 4, and vertical end walls 5. The rear wall 4 is provided with an upward extension 6, which serves as a guard to prevent the water from splashing over at the rear of the tub, and may also serve as a fixture to secure the tub or tray to a wall or other suitable support.

The tub or tray is constructed in the manner described and is preferably formed of a single piece of sheet metal from substantially the type of blank shown in Fig. 7, and which is made of galvanized or enameled sheet iron. As shown, the front and rear walls are provided with back-turned side flanges 7 and 8 which respectively overlap and are secured to the inclined front edges 9 and rearward extensions or flanges 10 of the side walls 5. The rear wall is also formed at its upper edge with a back-turned flange 11 united at its ends to the flanges 8 to form a reinforcing rim around the sides and top of said wall. Preferably the parts referred to are united by rivets and then electrically welded or soldered together, so as to form strong, durable and absolutely water proof joints.

It will be observed that the form of the one piece body is such as to secure maximum strength and durability, with economy of manufacture, as the parts may be cut or stamped out of sheet metal, bent into the described shape and firmly united in such a way as to reinforce each other. The upper edges of the front and end walls are provided with flanges 12 and 13 which are bent outwardly therefrom at a right angle and then bent downwardly, so as to provide guard rims which form broad surfaces around the margins at the top of the tub and at the same time greatly reinforce and strengthen the same. The side and front flanges are cut away at an angle at their adjacent ends, lapped and then welded or otherwise securely united.

In Figs. 4, 5 and 6 I have shown a tub or tray unit which may be employed as a hand or portable tub, adapted to be conveniently manipulated and transported from place to place. This tub unit is provided in its bottom with a drain outlet 14 of any suitable form, which may be connected with an outlet hose or pipe leading to a desired point of discharge. It is evident that a tub or tray when so constructed is light in weight, of maximum strength and durability of construction, and affords manifold advantages over the old style wash tubs or trays in common use.

The units or tub sections may be made permanent or stationary by securing them to a fixed support, as by mounting them upon a suitable stand or by extending fastening devices through the upward extension of the back into the wall of a room or any other

- stationary support. Stationary tubs, composed of any desired number of units or sections may also be easily made by assembling the sections together and fastening them in position. In Figs. 1 to 3 inclusive, 5 I have shown a double or two-section tub or tray of the stationary type formed by assembling two of the tub units. In assembling these units, adjacent ends thereof are brought together, and the flanges at such ends may be either flattened down or cut away and the ends united by a union or folded strip 5, bent over the edges of the abutting end walls and riveted, soldered or welded to said walls. This strip may be continued in the form of an extension over the 10 abutting ends of the rear wall extensions 6, as indicated at 16, and soldered or otherwise secured thereto to close the intervening gap 15 or joint. In addition, the abutting flanges 9 on the inner end walls and their extensions are united by bolts or rivets 17, whereby the 20 assembled sections or units will be held firmly connected. These sections or units 25 may be mounted upon a base or fastened or secured by fastenings passing through the back extension 6 to a wall or other support and the outlets 14 connected with the same or independent drain pipes.
- 30 I claim:—
1. A laundry tub or tray formed from a single piece of sheet metal and comprising a body formed of a bottom, a front wall, end
- walls, a back wall having an extension rising above the upper edges of the front and 35 end walls, the bottom and front walls being formed with flanges bent over upon and secured to the end walls, and the end walls and back wall formed with flanges secured to each other, the flanges upon the 40 back wall extending around the margins of the elevated portions thereof, and flanges at the upper edges of the front and end walls bent outward and downward to provide rim portions.
2. A tub comprising tub sections arranged end to end, each of said sections being formed from a single piece of sheet metal, each section comprising bottom, front, rear and end walls, the end walls having upward 45 extensions and being provided with side flanges, a union folded over upon and secured to the upper edges of the abutting end walls of the tub sections and provided with an extension secured to and overlying 50 the joint between the abutting edges of the rear wall extensions, and fastening members passing through the abutting flanges of said rear walls and extensions.
- 55 In testimony whereof I affix my signature 60 in presence of two witnesses.

OTTO E. ROSS.
